DESIGN FOR A TIEBACK OR SIMILAR ARTICLE

Harry Tashman, New York, N. Y.

Application May 25, 1944, Serial No. 113,753

Term of patent 7 years

(Cl. D21—1)

To all whom it may concern:

Be it known that Harry Tashman, a citizen of United States and resident of New York city, in the county of the Bronx and State of New York, has invented a new, original, and ornamental Design for a Tieback or Similar Article, of which the following is a specification, reference being had to the accompanying drawing, forming part thereof, and in which,

Fig. 1 is a front elevational view of the tieback, embodying my new design; and

Fig. 2 is a side edge view with parts in cross-section.

I claim:

The ornamental design for a tieback or similar article, substantially as shown.

HARRY TASHMAN.
